UNITED STATES PATENT OFFICE.

EDMUND H. LUNKEN, OF DENVER, COLORADO.

WINDOW.

SPECIFICATION forming part of Letters Patent No. 739,431, dated September 22, 1903.

Application filed February 13, 1903. Serial No. 143,161. (No model.)

To all whom it may concern:

Be it known that I, EDMUND H. LUNKEN, a citizen of the United States, residing at Denver, in the county of Denver and State of Colorado, have invented certain new and useful Improvements in Windows, of which the following is a full, clear, and exact description, reference being had to the accompanying drawings, forming part of this specification.

My invention relates to windows for buildings which have sliding sashes to be raised and lowered, such sashes consisting usually of the glass-carrying sashes, blind or shutter sashes, and outside screen-sashes; and it has for its object the improved construction of such windows, whereby their weather and dust proof qualities are increased, the efficiency of all of the working parts secured, combined with lightness, compactness, and durability, provision made for the raising of the sashes or any of them into a box or casing above and forming a continuation of the window-frame, as well as provision for having the blinds or shutters upon the inner side of the glass-carrying sashes or upon the outer side of the same, and also provision made for swinging the main glass-carrying sash bodily from its upper edge into the room to permit the outer side of the glass to be washed.

It also has for its object the various constructions and combinations of the parts, all as will be hereinafter more fully set forth, and specifically pointed out in the claims.

In the accompanying drawings, Figure 1, Sheet 1, is an inside elevation, partly in section, of a window embodying my present invention under one form of construction. Fig. 2, Sheet 1, is a sectional side elevation on the dotted line $x x$ of Fig. 1 looking to the left. Fig. 3, Sheet 2, is a view corresponding to Fig. 1 of my improved window under another form of construction. Fig. 4, Sheet 2, is a sectional side elevation on the dotted line $y y$ of Fig. 3 looking to the left. Fig. 5, Sheet 3, is an enlarged broken view corresponding to Fig. 2 to show the parts more plainly. Fig. 6, Sheet 3, is a similar view to Fig. 5, except that the glass-carrying sashes are of the ordinary standard construction and no provision is made for sliding them into a box or casing above the window-frame. Fig. 7, Sheet 3, is

an enlarged detail sectional view taken transversely of the meeting-rails of the glass-carrying sashes and showing a locking mechanism therefor. Fig. 8, Sheet 3, is an enlarged detail sectional plan view showing the guides for the lower glass-carrying sash. Fig. 9, Sheet 3, is an enlarged sectional detail of the lower corner of one of the shutters and its guides. Fig. 10, Sheet 4, is an enlarged sectional plan view on the dotted line $z z$ of Fig. 5. Fig. 11, Sheet 4, is an enlarged sectional plan view on the dotted line $a a$ of Fig. 5. Fig. 12, Sheet 4, is a broken sectional side elevation of the lower inner part of the window, showing the lower sash swung inward from its upper edge. Fig. 13, Sheet 4, is a perspective detail of the upper corner of the lower glass-carrying sash. Fig. 14, Sheet 4, is a sectional side elevation in detail of the upper part of the lower glass-carrying sash when swung inward. Fig. 15, Sheet 4, is a perspective detail of the lower part of the sliding strip for the lower glass-carrying sash and its guide. Fig. 16, Sheet 4, is a perspective view of the upper part of one of the metal boxes constituting the weight-wells.

The same numerals of reference are used to indicate identical parts in all the figures.

I will first describe my improved window under the constructions illustrated in Figs. 1, 2, 5, 10, 11, and 12, in connection with the detail views to be referred to in the description.

In the figures above referred to the frame surrounding the window-opening is composed of a metal pulley-stile 1 on each side, behind which is secured by screws or rivets a metal box or casing 2, Figs. 1, 10, and 16, with division-walls 3 to form the various weight-wells, a head 4, stool or sill 5, and pilaster-facings 6 on each side. The outer wall of the building 7 abuts against the outer side of the weight-box and the inner side of the pulley-stile 1, as seen in Fig. 10, and also across the top of the window-opening, as seen at 8, Fig. 11, though this latter finish is a mere detail, which forms no part of my present invention.

Above the top of the window-opening and forming a continuation of the frame is a box or casing 9 within the wall and shown in Figs. 1 and 2 as extending up through the

floor-supports 10 into the room above. The weight-boxes, however, do not extend higher than the head 4 of the window-opening, as seen in Fig. 1.

5 The guides for the various sashes are all contained in the inner sides of the pulley-stile, and in the construction of the figures mentioned (see Figs. 10 and 11) 11 is the upper glass-carrying sash, sliding between parting-strips 12 and 13, contained in recesses in the pulley-stile 1. The lower and main glass-carrying sash 14 slides between the parting-strip 13 and an interior slidable T-shaped strip 15, contained in a correspondingly-shaped 15 groove 16 in the pulley-stile 1. One of the pulleys for the lower sash 14 is shown at 17, Figs. 1 and 10, and 18 is its weight and 19 its cord or chain, these parts being of the usual or any suitable construction. The weight 20 for the upper sash, as seen by the dotted lines, Fig. 1, is at the lower part of the well-box when said sash is raised and closed, and its pulley 21 is in line with the pulley 17. As seen in Figs. 2 and 5, the upper sash when 25 closed has its top rail in close contact with the lower edge of a division-piece 22, standing vertically in the box or casing 9, which division-piece divides said box or casing into two compartments and serves in connection with 30 the upper rail of the upper sash to exclude all air and dust when the sashes are closed. In addition to being guided by the parting-strips 13 and the T-shaped guide-strips 15, which latter are just about the length of the 35 side rails of the lower frame or somewhat less, the exterior edges of the side rails of the lower sash are grooved, as seen at 23 in Figs. 10 and 11, so that when said sash is raised within the box 9 said grooves engage tongues or guides 40 56, confined in grooves in the pulley-stile 1 and projecting therefrom, as shown in Fig. 11. The parting-strips 13, however, continue unbroken to the top of the box or casing 9. When the two sashes are closed, their meeting-rails 24 and 25 are locked by any suitable 45 sash-fastener. I have, however, shown a preferred form of sash-fastener in Fig. 7, where a spring-projected bolt 26 is contained in a bore in the rail 24 and has its projecting end 50 engaging a socket in the rail 25. The interior projecting end of the bolt 26 is connected to a bell-crank lever 27, bearing against the rail 24 and provided with an operating pull-cord 28, by which the bolt can be 55 retracted to unlock the sashes, as will be readily understood. This feature, however, forms no part of my present invention, as any other suitable side locks or meeting-rail locks might be employed for the two sashes referred to.

Pivoted to the under side of the upper sash 11, preferably at its middle, is a pendent rod 29, (see Figs. 1, 2, and 12,) which in this instance is shown asserpentine in shape, though 60 it is rigid and the shape given it is more for ornament than anything else. This rod serves the double purpose of affording a means to

pull down the upper sash when the lower sash is raised and also to engage with the lower rail of the lower sash when the latter is swung 70 inward for the purpose of cleaning the outer side of the glass, as seen in Fig. 12. To thus draw inward the lower sash without detaching it from the frame, it is only necessary to slide up the strips 15, which are provided with 75 finger-hooks 30, Fig. 15, for ease of manipulation and whose lower ends are notched or grooved, as shown at 31, and then to raise the lower sash sufficiently for it to clear the shoulder 32, Fig. 12, at its bottom, whereupon the 80 sash can be drawn bodily inward at an incline, with the cords 19 engaging the notches 31 in the lower ends of the strip 15 and also notches 33, Fig. 13, in the grooves 23 at the upper edges of the sash, thus forming a flexible hinge 85 for the upper edge of the sash without the necessity of pivot-bolts to enable the sash to be drawn bodily inward at an incline, as seen in Fig. 12, and then the rod 29 is made to engage at its free end with any suitable aperture 90 34 in the lower rail of the sash. To replace the sash in its frame, it is only necessary to disconnect the rod 29 and then partially raise the upper sash 11, so as to get the rod 29 out of the way, whereupon the sash 14 may be 95 pushed back against the parting-strips 13 and the slides 15 be lowered to the bottom of their grooves, whereupon the two sashes are again in operative position for being raised and lowered in the ordinary manner.

I will now describe the shutters or blinds which in the figures above referred to are just outside of the glass-carrying sashes. Two of these shutters are represented, an upper one 35, which is the exterior one, and an inner 105 lower one 36. (See Figs. 5 and 11.) The sashes of these shutters are connected by cords 37, (see Fig. 9,) secured to the lower edges of the sashes and passing over pulleys 38, Fig. 6, in the pulley-stiles 1, and with their lower ends 110 attached to weights 20 in their appropriate compartments in the weight box or well 2. It is preferred that the weights for these shutters should overbalance the same, so that when they are pulled down and then released the 125 weights will automatically draw them up within the box or casing 9, as seen in Figs. 2 and 5. The side rails of the shutter-frames are grooved to receive tongues 39, Figs. 9 and 11, which are fastened therein by screws or other means 120 40 and which are confined in grooves 41 in the pulley-stile 1, said grooves extending the entire length of the window-frame and inclosing box or casing 9. As seen in Fig. 11, there is room in said grooves behind the tongues 125 39 for the free passage of the weight-cords.

A lug or plate 42, secured to the top rail of the outer shutter-sash, extends over and engages the top rail of the inner shutter-sash when both are raised within the box 9, as seen in Fig. 5, and the lower rail of the outer shutter-frame is provided with pendent rods 43, one at each side and having hooks 44 at their lower ends. When it is desired to close the

shutters, it is only necessary to draw down the rods 43 and engage the hooks 44 in recesses 45, Figs. 5, 6, and 10, which recesses are partially covered by locking-plates 46, 5 whereupon both shutters will lie side by side and will cover the upper half of the window-opening. The inner lower shutter may then be drawn down by hand and may be locked at any desired point by side bolts on its frame, 10 and when entirely closed by a spring-projected bolt 47, Fig. 2, beneath the sill 5 with a pull-button within the room and a projecting latch-piece under the sill, which engages with a perforated lug on the under side of the 15 shutter-frame when the latter is entirely down. As seen in Fig. 6, it is to be noted that when the lower shutter is entirely closed it thereby locks the hooked lower ends of the rods 43 in their recesses, so that the upper shutter can- 20 not be raised without first releasing and partly raising the lower shutter.

Just outside of the shutter-frames are two fly-screen frames 48 49, confined and traveling in grooves 50 and 51, respectively, of the 25 pulley-stile 1. (See Figs. 10 and 11.) These screens are operated in the usual manner and can be raised entirely within the box or casing 9, as seen in Figs. 2 and 5, to remain during the winter or at such times when it is de- 30 sirable to entirely uncover the window-opening. I consider this feature of the provision of a box or casing above the window-opening for the screens as an essential feature of my invention independent of the construction of 35 the other parts of the window, and, as seen in Fig. 6, the glass-carrying sashes are of the ordinary type and no box or casing is provided above them for them to be raised into, although I have shown such box or casing for 40 both the screens and the shutters. The shutters, however, need not have such box or casing over them and might, like the glass-carrying sashes, be of the ordinary or standard type. Again, in Figs. 3 and 4, where the 45 box or casing extends over all of the sliding frames, I have shown the shutter-frames as located inside of the glass-carrying frame, as this arrangement of parts may be preferred by some persons. The construction of all the 50 operating parts remains the same except the change in location and except that I have dispensed with the overhanging lug or plate 42. Hence I have preserved the same numerals of reference to designate the parts. In 55 addition I have provided a notched bar 52, which is pivoted at its upper end to the top rail of the outer shutter and passes through a staple 53 on the top rail of the inner shutter. The shutters can both be overbalanced, 60 as before, and the lower inner shutter may have a side lock 54 or a chain 55, engaging a pin on the sill 5, for holding the inner lower shutter locked, either completely down or at any point desired. By the manipulation of 65 the bar 52 and the engagement of any one of its notches with the staple 53 the relative positions of the shutters with respect to each

other may be regulated at will. For instance, the lower shutter may be locked entirely down, and by taking hold of the bar 52 70 the upper shutter may be drawn down to any extent desired to uncover the upper part of the window-opening, as will be readily understood.

While I have illustrated and described 75 weights as the means for balancing or over-balancing the various sashes, it is apparent that spring-balances, such as are sometimes used in window construction, might be substituted for the weights.

As a simple and efficient means for holding the main lower sash between its guide-strips 13 and 15 (see Fig. 8) against rattling and to exclude air and dust, I provide a spring-metal weather-strip 58, made of spring 85 sheet metal doubled upon itself, with its doubled portion secured in a kerf or groove in the strip 13 and with its divergent ends bearing between the inner side of the strip 13 and the outer side of the sash 14 on each 90 side of said sash, as clearly indicated in Fig. 8. Again, while I have shown but a single rod 29 secured to the middle of the lower rail of the upper sash 11, if desired two of such rods may be employed, the one being 95 secured at one side of the sash and the other at the opposite side of the sash, both serving to raise and lower the sash and serving as props for the lower sash 14 when swung inward to the position shown in Fig. 12.

By reference to Figs. 10 and 16 the manner of securing the metal division-walls 3 within the weight-box 2 is clearly indicated. The inner edges of said division-wall occupy grooves in the pulley-stiles, and their outer edges are 105 held in place by tongues 57, Fig. 16, punched from the outer walls of the sheet-metal box 2, which tongues are bent inward alternately on opposite sides of the outer edges of the division-walls to hold the same securely in their 110 properly-adjusted positions, as will be readily understood.

Subject-matter shown and described in this application but not claimed forms part of the subject-matter of my prior application filed 115 November 24, 1902, Serial No. 132,616, and is claimed therein.

Having thus fully described my invention, I claim—

1. In window construction, the combination 120 of a frame, a glass-carrying sash slidable therein, means for balancing said sash, an interior guide-strip for said sash slidable in said frame and adapted to be raised above the same to permit the latter to be swung bodily inward, and means for forming a hinge connection at the upper edge of said sash, substantially as described.

2. In window construction, the combination 130 of a frame, a glass-carrying sash slidable therein and supported on weighted cords, an interior guide-strip for said sash slidable in said frame and adapted to be raised above the same to permit the latter to be swung bodily

inward, and means for engaging said cords from displacement so that they serve as hinge members for the upper edge of said sash, substantially as described.

5. In window construction, the combination of a frame, a glass-carrying sash slideable therein and supported on weighted cords, an interior guide-strip for said sash slideable in said frame and adapted to be raised above the sash to permit the latter to be swung bodily inward, means for engaging said cords from displacement so that they serve as hinge members for the upper edge of the sash, and a propping-rod for holding the lower edge of the sash away from the frame, substantially as described.

4. In window construction, the combination of a frame, a glass-carrying sash slideable therein and supported on weighted cords, an interior guide-strip for said sash slideable in said frame and adapted to be raised above the sash to permit the latter to be swung bodily inward, means for engaging said cords from displacement so that they serve as hinge members for the upper edge of said sash, an upper slideable sash in the frame, and a rod hinged to the lower edge of said sash and serving as

a means for raising and lowering the sash and for supporting the first-named sash in its inclined position when swung inward, substantially as described. 30

5. In window construction, the combination with the pulley-stile, of a sheet-metal weight-box secured to the outer side thereof, vertical metal division-walls forming individual wells for the weights in said box, and punched-out tongue connections for supporting the outer edges of said division-walls in proper position in the weight-box, substantially as described. 35

6. In window construction, the combination of the frame, sliding shutters therein provided with grooves in their outer edges, tongues secured in said grooves, grooves in the pulley-stile for said tongues, of a depth greater than the projection of the tongues to permit the passage of weight-cords whose lower ends are secured at the lower ends of the sashes, substantially as described. 40 45

EDMUND H. LUNKEN.
